CLAIM

The ornamental design for a payment terminal as shown and described.

DESCRIPTION

FIG. 1: is the front view of a payment terminal showing my new design;

FIG. 2: is a rear view thereof;

FIG. 3: is the bottom view thereof;

FIG. 4: is the top view thereof;

FIG. 5: is a right-side view thereof;

FIG. 6: is a left-side view thereof;

FIG. 7: is a bottom-right perspective view thereof; and

FIG. 8: is a top-left perspective view thereof.

FIG. 9: is the front view of a payment terminal showing the second embodiment of my new design;

FIG. 10: is a rear view thereof;

FIG. 11: is the bottom view thereof;

FIG. 12: is the top view thereof;

FIG. 13: is a right-side view thereof;

FIG. 14: is a left-side view thereof;

FIG. 15: is a bottom-right perspective view thereof; and,

FIG. 16: is a top-left perspective view thereof.

The broken lines in the drawings depict portions of the payment terminal that form no part of the claimed design.
